United States Patent Office

Des. 185,570
Patented June 23, 1959

185,570

SWIMMING POOL

Donald E. Pruess, White Plains, N.Y.

Application December 19, 1958, Serial No. 53,826

Term of patent 14 years

(Cl. D13—1)

FIG. 1

Des. 185,570

PAGE 2

Des. 185,570

The essential features of my design reside in the portions shown in full lines.

I claim:

The ornamental design for a swimming pool, as shown and described.
